UNITED STATES PATENT OFFICE.

JOHN F. DUBY, OF BOSTON, MASSACHUSETTS.

ROTARY EXPLOSIVE-ENGINE.

1,293,733.

Specification of Letters Patent. Patented Feb. 11, 1919.

Application filed March 22, 1918. Serial No. 223,398.

To all whom it may concern:

Be it known that I, JOHN F. DUBY, a citizen of the United States, residing at Boston, in the county of Suffolk and State of Massachusetts, have invented new and useful Improvements in Rotary Explosive-Engines, of which the following is a specification.

This invention has relation particularly to multiple cylinder, internal combustion engines, of the four stroke cycle type including a rotor having a group of cylinders, arranged with their axes substantially parallel to the axis of the rotor and provided with pistons which are operated to drive a shaft 10 at an angle to the axis of the rotor.

The principal objects of the invention are to attain simplicity of construction and efficiency of action of engines of this class, and especially to attain freedom from noise and vibration such as is ordinarily caused by reciprocating pistons and connecting-rods. More specifically, it is an object of the invention to provide a multiple cylinder engine capable of transmitting rotary motion to a driven shaft without the employment of cranks or cams. A further object is to simplify and improve the valve construction of rotary engines.

To this end, an engine embodying my improved engine comprises a rotor connected to drive and rotate in unison with a driven shaft, but on an axis which is at an angle to the shaft, and is provided with cylinders, the pistons of which are also connected to the driven shaft in such manner that the explosion in the cylinders will transmit rotary motion to the driven shaft without reciprocation of the pistons relatively to the said shaft and a rotor-supporting shaft coaxial 40 with the rotor. Said supporting shaft is geared to the rotor to rotate in timed relation to the latter, and is constructed to provide a supply conduit for the explosive mixture, an exhaust conduit for the products of combustion, a supply or intake port through which the explosive mixture is permitted to pass to the cylinders, and an exhaust port through which the products of combustion are permitted to pass from the cylinders to the exhaust conduit. The said shaft, therefore, provides intake and exhaust valves and is hereinafter referred to as a valve shaft.

The invention further consists in such novel features of construction and combinations of parts as will hereinafter be more fully described and pointed out in the claims.

Referring to the drawings, in which like characters of reference designate corresponding parts throughout the several views,—

Figure 1 is a view partly in side elevation and partly in longitudinal vertical section, showing the invention embodied in a three-cylinder explosive engine.

Fig. 2 is a section on the line 2—2 of Fig. 1.

Fig. 3 is a section on the line 3—3 of Fig. 1.

Fig. 4 is a section on the line 4—4 of Fig. 1.

Figs. 5, 6, 7, and 8 are transverse sections through the rotary valve showing the inlet and exhaust ports at the beginning of each of the four piston strokes of a three-cylinder engine.

Figs. 9, 10, 11 and 12 are similar views, showing a modified arrangement of the ports.

As illustrated in the drawings, the engine has a base 10 and uprights 11 and 12, which are provided respectively with bearings 13 and 14, one inclined relatively to the other. Journaled in the bearing 13 is the driven shaft 15 carrying a driving head 16 which is preferably a disk. A rotor 17 is mounted 80 to rotate upon one end portion of a rotary shaft 18, which I call the valve shaft for the reason hereinbefore stated, the other end of said valve shaft being journaled in the bearing 14 and held therein between an annular 90 flange 19 and a collar 20 and nut 21.

A universal joint 22 including a member 22^a attached to and coaxial with the rotor 17, and a member 22^b coaxial with the shaft 15, connects the rotor with the shaft, so that the 95 weight of the rotor is distributed between the bearings 13 and 14, and so that said rotor and said driven shaft are caused to rotate in unison. The rotor 17 is provided with cylinders 23, each cylinder having a piston 24, 100 connected through a wrist-pin 25, connecting-rod 26, and a universal joint including members 27 and 28, with the marginal portion of the head 16, at points spaced from the axis of the driven shaft.

The valve shaft 18 is provided with an inlet channel or conduit 30 which surrounds a central exhaust channel or conduit 31 and is provided with an inlet port 32, which receives the explosive mixture from an annular 110 chamber 35 connected with the supply pipe 34, and with a supply port 32^a which delivers the explosive mixture successively in radial passages 36 in the rotor communicating with

the cylinders 23. The exhaust conduit 31 is provided with an exhaust port 33, which also communicates successively with the passages 36. The explosive mixture thus admitted is compressed in the cylinders and ignited in the usual manner, and the products of combustion are then exhausted through the passages 36, the exhaust port 33, and exhaust conduit 31.

- 10 On the rotor 17 is a hub 40, surrounding the central valve shaft 18. A gear 41 fixed to said hub, drives a gear 42 which is fixed to the valve shaft 18 through the intermediate pinions 43 and 44, which are mounted upon the stud 45, said gearing being in the ratio of three to two, so that the valve shaft 18 will make three revolutions to every two revolutions of the rotor. This will cause the intake and exhaust to occur at the proper intervals, as illustrated by Figs. 5, 6, 7, and 8, which show the relative positions of the intake and exhaust ports of the shaft 18 and the radial passages 36 leading to the cylinders, for each of the four strokes of 25 the pistons. The cylinders are conventionally indicated by the Roman numerals I, II and III.

30 The engine may be designed with double intake and exhaust ports, instead of the single ports already described, in which case the central shaft 18 and the rotor will be geared together in the ratio of one and one-half to two, said shaft making one and one-half rotations to every two rotations of 35 the rotor. Figs. 9, 10, 11 and 12 illustrate this embodiment of the invention and show the relative positions of the supply and exhaust ports of the central shaft and the passages leading to the cylinders in the 40 rotor.

45 Obviously the invention is adapted to be embodied in engines having various multiples of cylinders, for example, by gearing the central shaft to the rotor so that the former will make two and one-half rotations to every two of the latter, the engine may be constructed with five cylinders.

50 The spark plugs 46 may be ignited by any desired means. I prefer, however, to employ the jump-spark system and have shown a primary circuit, one terminal of which is suitably grounded on the framework of the engine, the other terminal being a stationary contact 47, (Figs. 1 and 4). A rotating contact maker 48 on the shaft 18 intermittently closes this circuit. The secondary circuit of this system also has one terminal grounded on the frame work of the engine, while the other is led by a 55 contact finger 49 to a conducting ring 50 which encircles the hub 40 of the rotor. The ring includes an annular body 50 of insulating material and three contact blocks 51, insulated from each other and from the rotor 60 by said body and connected in any suitable manner, as by the contact fingers 52 with the spark-plugs 46. The stationary contact 47 of the primary circuit is fixed to a ring 53, loosely mounted upon an annular flange 37 integral with the bearing 14, and 65 is maintained in fixed radial relation with said contact maker 48 by means of a spring 54 which is carried on the engine frame and which bears against a segment 55 on the ring 53. A handle 56 is provided for re- 70 rotating said ring slightly upon the shaft, so as to vary the radial adjustment of the contact, thereby advancing or retarding the spark in the cylinders.

75 The reciprocation of the pistons in the cylinders causes the pistons to act on the head to rotate the latter and the driven shaft 15 in a well known manner.

80 It will be seen that an engine designed to embody the essential features of this invention, as hereinbefore set forth, will possess many advantages, among which may be mentioned noiselessness in operation and freedom from vibration. This is due to the fact that while there is relative movement 85 between the pistons and the cylinders, there is no reciprocation of the pistons with respect to the driven shaft 15. The engine may be adapted to be cooled by any suitable cooling system.

90 Various changes in the form, proportions, and minor details of the invention may be resorted to without departing from the spirit and scope thereof, and I consider myself entitled to all such variations as may 100 be within the terms of my claims.

I claim:

1. An engine comprising spaced apart bearings, one inclined relatively to the other, a rotary valve shaft journaled in one of 105 said bearings, a rotor coaxial with and supported by the valve shaft between said bearings and provided with cylinders and with passages extending from said cylinders to the rotor hub, means for imparting timed 110 rotation from the rotor to the valve shaft, said shaft being provided with means for admitting an explosive mixture to said passages, and with means for exhausting products of combustion therefrom, a driven 115 shaft journaled in the other bearing, the axes of the rotor and driven shaft intersecting, and one being inclined relatively to the other, pistons in said cylinders, and driving connections between said pistons and driven 120 shaft including universal joints spaced outwardly from the axes of the rotor and driven shaft, the weight of the rotor being distributed between said bearings.

125 2. An engine comprising spaced apart bearings, one inclined relatively to the other, a rotary valve shaft journaled in one of said bearings, a rotor coaxial with and supported by the valve shaft between said bearings and provided with cylinders and with 130

- passages extending from said cylinders to the rotor hub, means for imparting timed rotation from the rotor to the valve shaft, said shaft being provided with means for admitting an explosive mixture to said passages, and with means for exhausting products of combustion therefrom, a driven shaft journalized in the other bearing, the axes of the rotor and driven shaft intersecting and one being inclined relatively to the other, a universal joint connecting the rotor and with the driven shaft at the intersection of said axes, pistons in said cylinders, and driving connections between said pistons and driven shaft including universal joints spaced outwardly from the axes of the rotor and driven shaft, the weight of the rotor being distributed between said bearings.
- 20 3. An engine comprising spaced apart bearings, one inclined relatively to the other, a rotary valve shaft journalized in one of said bearings and provided with supply and exhaust conduits and with ports communicating therewith, a rotor coaxial with and supported by said valve shaft between said bearings, said rotor being provided with cylinders and with radial passages communicating therewith, arranged to cooperate with said ports, means for imparting timed rotation from the rotor to the valve shaft, a driven shaft journalized in the other bearing, the axes of the valve shaft and driven shaft intersecting, and one being inclined relatively to the other, a universal joint connecting the rotor and the driven shaft at the intersection of their axes, pistons in said cylinders, and connections between said pistons and driven shaft, including rods attached to the pistons, a head attached to the driven shaft, and universal joints connecting said joints and head at points spaced outwardly from the first-mentioned universal joint, the weight of the rotor being distributed between said bearings.
4. An engine comprising a rotary valve shaft, a fixed bearing therefor, a rotor coaxial with and supported by said shaft, and provided with cylinders and with passages extending from said cylinders to the rotor hub, means for imparting timed rotation from the rotor to the valve shaft, said shaft being provided with means for admitting an explosive mixture to said passages, and with means for exhausting products of combustion therefrom, pistons in said cylinders, means for igniting the explosive mixture in said cylinders in timed relation with said rotor, a driven shaft at an angle to the valve shaft and rotor, and means for imparting rotary movement from the rotor to the driven shaft.
5. An engine comprising a rotary valve
- shaft, a fixed bearing therefor, a rotor coaxial with and supported by said shaft, and provided with cylinders and with passages extending from said cylinders to the rotor hub, means for imparting timed rotation from the rotor to the valve shaft, said shaft being provided with means for admitting an explosive mixture to said passages, and with means for exhausting products of combustion therefrom, pistons in said cylinders, an ignition system for firing the explosive mixture in said cylinders, ignition-controlling means having provisions for either advancing or retarding the spark, a driven shaft at an angle to the valve shaft and rotor, and means for imparting rotary movement from the rotor to the driven shaft.
6. An engine comprising a rotary valve shaft, a fixed bearing therefor, a rotor coaxial with and supported by said shaft, and provided with cylinders and with passages extending from said cylinders to the rotor hub, means for imparting timed rotation from the rotor to the valve shaft, said shaft being provided with means for admitting an explosive mixture to said passages, and with means for exhausting products of combustion therefrom, pistons in said cylinders, a jump-spark ignition system having primary and secondary circuits, a stationary contact in said primary circuit, a contact maker on said valve shaft, a stationary contact in said secondary circuit, a conducting ring on said rotor, spark plugs in the cylinders connected with said ring, means for changing the radial position of said primary circuit contact with relation to said primary circuit contact maker, to vary the time of the explosion in the cylinders, a driven shaft at an angle to the valve shaft and rotor, and means for imparting rotary movement from the rotor to the driven shaft.
7. An engine comprising a rotary valve shaft, a fixed bearing therefor, a rotor coaxial with and supported by said shaft, and provided with cylinders and with passages extending from said cylinders to the rotor hub, differential gearing for imparting timed rotation from the rotor to the valve shaft, the said shaft being provided with supply and exhaust conduits, and with intake and exhaust ports communicating with said conduits, and adapted to cooperate with said passages, means for igniting an explosive mixture in said cylinders in timed relation with said rotor, a driven shaft at an angle to the valve shaft and rotor, and means for imparting rotary movement from the rotor to the driven shaft.

In testimony whereof I have affixed my signature.

JOHN F. DUBY.
